BAG FORMING PROCESS

Spencer U. Boehmer, Glen Ellyn, Ill.

Application June 30, 1937, Serial No. 151,076

2 Claims. (Cl. 93—35)

This invention relates to processes for forming bags or containers of flexible material, such as paper, "cellophane", and the like, and also to the structure of the bags. A particular object is to provide such a bag so formed that it may be sealed when filled with the substance which it is to contain, and then may be conveniently opened and again sealed, so that some of the substance may be removed and the remainder may be fully protected from exposure to the air, by again sealing the bag.

Of the accompanying drawing Fig. 1 is an elevation of the mandrel which I provide; Fig. 2 is an end view of the mandrel; Fig. 3 is an elevation of the mandrel with the bag material thereon in the process of forming; Fig. 4 is an end view of the same; Fig. 5 is a longitudinal sectional view of the same; Fig. 6 is an elevation of the bag with one end closed and with the mandrel removed therefrom; and Fig. 7 is a similar view with the other end of the bag closed.

The mandrel consists of a tube 10 of any suitable material, preferably material having a smooth outer surface. The outside diameter of the tube is chosen as substantially the same as the inner diameter of the bag when finished. In one end of the tube is slipped another tube 11, so that the outer end of the inner tube will project from the main tube a suitable distance, preferably one half inch or more. These tubes are fastened together in any suitable manner, either by forcing the inner tube in the outer one, or by soldering, or otherwise. While I prefer this method of forming the mandrel, yet it may be formed by merely turning down the end of the main tube so as to form a circumferentially inwardly offset portion with the shoulder 12 a suitable distance from the end. This distance, however, may be varied at pleasure, depending on the needs.

In forming the bag, a collar 9, of any suitable material, but of material of suitable rigidity, is removably positioned on the projecting end of the tube 11, the thickness of the collar preferably being such as to bring the outer surface substantially flush with the outer surface of the main tube.

A sheet of the material of which the bag is to be formed is then wrapped around the mandrel and collar, so as to form the tubular member 13 with its edge 14 projecting a material distance beyond the outer end of the collar 9. The end 14 of the bag material is then twisted and then turned inwardly within the collar, so as to substantially seal that end of the bag; and the bag, including the collar, is then slipped from the

mandrel. If desired, the outer surface of the collar may be coated with adhesive material so that it will be permanently fastened to the bag when it is completed. To assist in removing the mandrel the unsealed end of the bag is formed a material distance inwardly from the end 15 of the mandrel, so that this portion of the mandrel may be grasped as the bag is being removed.

When the bag is thus removed from the mandrel, it may be filled with any desired substance, such as candy, soup pellets, or the like, and the end 17 of the bag then may be permanently sealed in any desired manner. When it is desired to remove any of the contained substance the end 16 of the bag is opened by pulling the end of the bag out of the collar; the substance then may be entirely or partly removed; and if only partly removed the bag may be again closed by twisting the end and forcing it back in the collar.

The bag may be composed of any suitable material, such as paper or "cellophane", or even of metal foil. The collar, however, should be formed of stiff material so as to retain its shape as the end is forced therein or pulled out. The collar may be permanently fixed to the bag material, or it may be movable therein. In the latter case it may be shoved inwardly more and more as the contained substance is removed, so as to maintain a filled condition of the bag at all times. The collar not only forms a means for allowing the end of the bag to be twisted and forced within the collar, and for holding the bag end in shape, but it also forms a rigid and suitable bottom for improving the appearance of the bag and for a base on which the bag may rest, if that is desired.

I claim as my invention:

1. A process for forming a bag consisting in mounting a bag collar removably on one end of an elongated tubular member, in then wrapping a sheet of bag material around the tubular member and the collar so that one edge of the sheet projects a material distance beyond the tubular member and the collar, and so that the other end of the tubular member projects a material distance beyond the sheet edge adjacent that end, and in then twisting and forcing the projecting edge of the sheet into the collar, and in then removing the tubular member from the sheet and the collar, leaving the collar in the bag thus formed as a part thereof.

2. A process for forming a bag consisting in mounting a tubular member on one end of a mandrel, in then placing a piece of bag material

around the mandrel and the tubular member so that one edge of the piece projects a material distance beyond the mandrel and the tubular member, and so that the other end of the mandrel projects a material distance beyond the piece of bag material, and in then twisting and forc-

ing the projecting piece edge inwardly, and in then removing the mandrel from the bag material piece and the tubular member, leaving the tubular member in the bag thus formed as a part thereof.

SPENCER U. BOEHMER.
